UNITED STATES PATENT OFFICE.

WILLIAM F. BRETTSCHEIDER, OF ST. PAUL, MINNESOTA.

SIGNAL.

Application filed December 12, 1923. Serial No. 680,251.

My invention relates to signals or direction indicators for motor vehicles and has for its object to provide means for indicating to the public the direction which the 5 motorist intends to travel.

Another object of the invention is to provide means whereby persons positioned on all sides of the vehicle may be simultaneously informed as to the purpose of the 10 driver.

Another object of the invention is to provide signals both in the rear and the front of the vehicle which are controlled by a single controlling means to simultaneously 15 operate the same.

A feature of the invention resides in providing the front signaling means with two or more signals facing in different directions and to provide means for simultaneously 20 illuminating all signals of like character of said signaling means.

A still further feature of the invention resides in providing separate signaling means for indicating that the motorist 25 wishes to travel to the right, to the left or forward, which signaling means are confined to a limited space.

Another object of the invention consists of providing means for illuminating all of 30 the signals of each kind from a single illuminating member.

Another object of the invention resides in providing a casing having transparent windows arranged along three sides of the 35 same and of providing similar letters upon all of said windows and to provide means for simultaneously illuminating the corresponding letters on each of said windows by means of separate illuminating members 40 for each class of letters.

Another object of the invention resides in providing radially positioned walls which divide the casing into two compartments and to position individual illuminating 45 members in each of said compartments, said walls being arranged to direct the rays of light to certain portions of each of said windows.

Another feature of the invention resides in so connecting up the device that the tail light of the vehicle is turned off at the time the rear signal or direction indicator is rendered operative.

Other features of the invention reside in 50 the detailed construction thereof as will be

more fully brought out in the specification and claims relating thereto.

In the drawings illustrating my invention in one form Figure 1 is a front elevational view of the type of direction indicator employed at the front of the vehicle. 60

Figure 2 is a sectional view taken on line 2-2 of Figure 1.

Figure 3 is a sectional view taken on line 3-3 of Figure 2. 65

Figure 4 is a sectional view taken on line 4-4 of Figure 3.

Figure 5 is a perspective view of the type of direction indicator mounted upon the rear of the vehicle. 70

Figure 6 is a sectional view taken on line 6-6 of Figure 5.

Figure 7 is a sectional view of the switch for controlling the operation of the invention. 75

Figure 8 is a wiring diagram illustrating the installation of my invention.

With direction indicators it is highly essential that persons on all sides of the vehicle be informed as to the intent of the 80 motorist so that they may govern themselves accordingly. It is also essential that the signaling or indicating devices be simultaneously operated so that no confusion occurs. At the same time it is highly desirable 85 to have a simple and effective device which utilizes a minimum amount of current from the battery. My invention fully complies with these requirements as will become apparent from the following description 90 thereof.

My invention consists primarily of a direction indicator or signal A which is positioned at the front of the vehicle and another direction indicator B positioned at the rear 95 of the vehicle. The signal B is provided with a window 9 on the face thereof on which is formed the letter L indicated at 10 and the letter R indicated at 11, said latter letter being positioned within the vertex of 100 the letter L. Upon illuminating the portion of the signal comprising the letter L persons to the rear of the vehicle are informed that the motorist intends to travel to the right. By illuminating the portion 105 of the signal comprising the letter L persons to the rear of the vehicle are informed that the motorist intends to travel toward the left. The signal A is constructed in a similar manner, having, however, three 110

windows 12, 13 and 14 on which the respective letters 10 and 11 appear. Like letters on all of the windows are simultaneously illuminated so that the observers can see the 5 same letter from all sides of the vehicle.

The construction of the signal or direction indicator B is clearly shown in Figures 5 and 6. This device consists of a casing 15 which is open at the front and which is formed 10 with ears 16 projecting inwardly into the same. Within the said casing is provided a partition comprising a vertical wall 17 and a horizontal wall 18 which are arranged as shown in dotted lines in Figure 5 and which 15 are also formed with ears 19 corresponding to the ears 16 on the exterior walls of the casing. The two walls 17 and 18 divide the interior of the casing 15 into two compartments 20 and 21 of which the compartment 21 is angular in formation and the compartment 20 is rectangular, being positioned in the vertex of the angle of compartment 21. Across the front of the casing 15 is positioned the window 10 previously referred to which is supported against the ears 18 and 19 and which is held in place by a frame 22 secured to casing 15 by means of screws 23. This window may be made of a single piece of glass or may be made of separate pieces so that the compartments 20 and 21 may be closed by separate closure members. In the drawings I have illustrated a piece of green glass 24 covering the opening to compartment 20 and a piece of red glass 25 covering the compartment 21. The frame 22 is so constructed with a vertical bar 26 and a horizontal bar 27 so that the portion of the red glass indicated at 25, visible through the same, exactly simulates the shape of the 40 letter L. Immediately in back of the green glass 24 is positioned a stencil 28 constructed of some opaque material, which together with the frame provides a green letter R similar to the red letter L.

45 Within the two compartments 20 and 21 of casing 15 are positioned electric lights 29 and 30 which will be lighted in a manner to be presently described. It can readily be seen by this arrangement that when the light 30 is lighted that the interior of the 50 compartment 20 is illuminated and the red letter R caused to be displayed to observers of the signal. In a similar manner, when the light 29 is lighted the green letter L is also illuminated. If desired a window 10 as before stated can be made of a single piece of glass having a single color for both the L and the R, or clear glass used and the different colors painted thereon.

55 The device used upon the front of the vehicle and indicating the direction of the travel of the motorist is similar to that shown in Figures 5 and 6. In this device, however, the three windows 12, 13 and 14 are employed instead of the single window

10 there illustrated. In this device a casing 31 is employed which consists of a solid back 32 connected to a horizontal partition 33 near the upper portion thereof to which posts 34, 35, 36 and 37 situated at the corners 70 of the casing are attached. At the upper portion of the casing the posts 34, 35, 36 and 37 are connected together by horizontal bars 38 and 39 and at the bottom the same are connected by similar bars which hold the respective parts together to form a substantial construction. In this form of the invention it is advantageous to form the device of a single casting in which all of the parts are cast integrally, though it can readily be 80 understood that the same may be otherwise constructed without involving further invention. Within the interior of the casing A in addition to the partition 33 are placed three upwardly inclined partitions 40, 41 and 42 which are pyramidal in formation and are connected to one another and to the back 32 as well as the posts 34, 35, 36 and 37. These partitions terminate with their lower edges 85 indicated at 43 flush with the interior surfaces of the windows 12, 13 and 14 and serve to divide the lower portion of casing A into two compartments indicated at 44 and 45. In addition to these partitions a number of vertical walls 46 and 47 are employed 90 which issue outwardly from the interior of the two posts 36 and 37 and intersect the partition 41. In conjunction with these two vertical walls and the back 32 I employ three other vertical walls 48, 49 and 50 which have 95 their edges 51 positioned along the surface of the windows 12, 13 and 14 and which intersect the partitions 40, 41 and 42 and having the said edges 51 intersecting the edges 43 at right angles thereto as clearly 100 shown in Figure 1. These vertical walls are covered with downwardly sloping roofs 52, 53 and 54 which extend up to the horizontal partition 33 so that with this arrangement 105 the space 44 is adapted to communicate with all portions of the three R's displayed through the windows 12, 13 and 14, whereas the compartment 45 is adapted to communicate with all portions of the three L's displayed through the same windows.

Above partition 33 is formed a compartment indicated at 57 in the casing A which is of considerably less height than the compartment below the same. This compartment communicates with openings 58 positioned above the windows 12, 13 and 14 in which similar windows 59 may be placed and supported.

For supporting the windows 12, 13 and 14 within the casing A the posts 34, 35, 36 and 37 are made with oppositely facing grooves 115 55 in which the panes of glass indicated at 56 and forming the windows 12, 13 and 14 may be slid from the bottom of the said casing. As is the case with the form of the 120 130

invention used upon the rear of the vehicle stencils shown at 60 and 61 may be employed to form the letters L and R upon the respective windows 12, 13 and 14 and an arrow upon the windows 59, or these characters may be secured in any other suitable manner as before stated.

Within the compartments 57, 44 and 45 are positioned three electric lights 62, 63 and 64 which are placed in sockets 65 secured to the wall 32 of the casing. These lights when illuminated as clearly becomes evident will simultaneously illuminate the characters upon the respective windows communicating with the above mentioned compartments so that the signal is given in all three directions at the same time by a single lamp. For illuminating the stems of the three L's the walls 46, 47, 48, 49 and 50 and the roofs 54, 52 and 53 form radially extending passageways 66, 67 and 68 which conduct the light rays from the center of the electric light 64 to all portions of the said letters, so that upon the lighting of this light the letters are clearly illuminated throughout their entire extent with equal brilliancy.

For inclosing the casing and for holding the glass panes 56 and 58 in place I provide a detachable cover 69 and a detachable base 70 adapted to be secured upon said casing A by means of screws 71 and 72 screwed into the several parts 34, 35, 36 and 37. The bottom 70 has a boss 171 formed upon the lower portion of the same to which any suitable bracket such as indicated at 172 may be attached to mount the structure where desired.

The signal A may be supported by means of the bracket 172 upon any suitable portion of the vehicle proper at the front thereof, where the same may be readily visible from the two sides and the front of the same. If desired, member A may be positioned upon the hood or attached to the radiator or, if preferable, may be mounted upon the fender or top of the vehicle. In a similar manner the casing B may be positioned upon the rear fender or attached to the body of the vehicle at any rearward portion of the same where said signal may be easily perceived by the public.

In connecting up the device reference is to be had to Figure 8 in which the three lights 62, 63 and 64 which are positioned in casing A are indicated at the upper portion of said figure and the two lights 29 and 30 positioned in casing B are indicated at the lower portion of said figure. In addition, the vehicle battery is shown at 73 and the dash lamp and tail light at 74 and 75 respectively. In addition to this construction a special switch is indicated at C which is shown in detail in Figure 7. This switch consists of a base 76 which has rotat-

ably mounted upon it a flanged shaft 78 formed with a central bore 79 extending through the same. This shaft has attached to it a swinging arm 80 which is held in place thereon by means of a nob 81 through which said arm may be rotated. Arm 80 is adapted to contact with three fixed contacts 82, 83 and 84, all secured to the base 76. As illustrated, the base 76 is formed hollow and within the same is mounted a fixed, arced contact member 85 which is directly connected to the fixed contact 83. In addition, a yieldable contact member 87 is secured to the base 76 opposite to the contact 85. These contacts form a normally open circuit closer which is adapted to be closed by the rotating of a threaded spindle 88 screwable within the shaft 78 and operable by a nob 89 secured upon the end of the same. Upon the rotating of the nob 89 inwardly the yieldable contact member 87 is caused to engage the fixed contact member 85 and to close a circuit connected therewith.

The manner of connecting up the various elements of my invention to secure the signal desired can best be understood in referring to Figure 8. The battery 73, being the battery of the vehicle is grounded at one side and is connected at its other side by means of a conductor 90 to the swinging arm 80 of switch C. This switch feeds the various signals of the invention. To the various contact members 82, 83 and 84 are connected circuits 91, 92 and 93 which are all grounded at their extreme ends. In the circuit 91 are connected in series the lights 64 and 29, and in the circuit 93 are connected in series the lights 63 and 30; while the circuit 92 contains the light 62 alone. With this arrangement it can readily be seen that as the nob 81 is rotated that either the right, forward or left turn signals may be selectively operated to indicate the direction the motorist intends to travel.

In addition to the circuits for controlling these various signal lights I employ another grounded circuit 94 which is connected to the yieldable contact member 87 previously referred to. This circuit contains the dash lamp 74 and the tail light 75 which are connected in series in the usual manner. When the switch arm 80 is in contact with the contact 83 the light 62 is normally maintained lit and a circuit may be had to the tail light 75 and dash lamp 74 by the manipulation of the nob 89. With this arrangement the light 62 may be maintained lit during the evening and by closing the circuit 94 through the operation of the nob 89 the tail light 75 and dash lamp are fed at the same time. As soon as either of the lights 64 or 63 are lit by the shifting of the switch arm 80 to the contact 82 or 84 the tail lamp 75 is deprived of current and only the signal lamps at the

rear and front of the vehicle are lit, thereby preventing confusion to the observers.

For daytime use the switch arm 80 is normally positioned between any of the contacts, thereby maintaining circuits 91, 92 and 93 open and the nob 89 is so turned that the circuit 94 is also open. With this arrangement either the right, left or forward lights of the signal can be lit without causing the tail light to be lit at the same time.

To enable the motorist to determine whether the various signals of the invention are operating when the switch is manipulated I provide three openings 100 in the rear wall 32 of casing A, which openings communicate with the respective compartments 57, 44 and 45 and which allow the portion of the light within the same to shine through the said openings as visible from the driver's seat when the casing A is positioned upon the radiator or some forward portion of the vehicle. In this matter the motorist at all times is advised whether the signal is in operation or not.

The advantages of my invention are manifest. A system is provided in which the tail light of the vehicle becomes extinguished upon operating the signal associated therewith so that confusion to the observers from the rear of the vehicle cannot occur. When the vehicle is traveling in a forward direction the signal indicating forward travel is maintained lit. But three lights are used for illuminating the signals each light illuminating three separate signals, which signals are so arranged as to be visible from three sides of the vehicle. An extremely simple construction is secured in which the parts may be readily formed by manufacturing methods now in common use, so that the device may be readily manufactured and assembled. The particular arrangement of the signal members permits of a device of small and compact size to be constructed, so that the device is neat in appearance and requires only a minimum amount of material in its construction.

I claim:

1. A direction indicator including a series of indicating faces, indicating L and R characters formed on said indicating faces, separate light compartments formed in said direction indicator, one of said compartments having its openings limited by and being adapted to illuminate all of the R's in the indicating faces simultaneously and the other of said compartments being adapted to illuminate all of the L's simultaneously in said indicating faces, the R's of said indicating faces being formed within the area of the L formed therein, but each being independent of each other in formation and indication, to form a compact

2. A casing polygonal in cross section, a plurality of windows positioned along at least three of the sides thereof, a letter L formed on each of said windows, another letter formed on said windows and positioned in the vertexes of said letters L, upwardly inclined, radially extending partitions issuing from the lines of separation of the legs of said L's and said other letters, radially extending vertically positioned walls issuing from the lines of division of said stems of said L's and said other letters and from the corners of said casing, intersecting said partitions to form two compartments communicating with all of said other letters and said L's and means within each of said compartments for simultaneously illuminating all of said L's or said other letters.

3. A casing polygonal in cross section, a plurality of windows positioned along at least three of the sides thereof, an angular letter formed on each of said windows, a letter R formed on said windows and positioned in the vertexes of said angular letter, upwardly inclined, radially extending partitions issuing from the lines of separation of the legs of said angular letters and said R's, radially extending vertically positioned walls issuing from the lines of division of said stems of said angular letters and said R's and from the corners of said casing, intersecting said partitions to form two compartments communicating with all of said R's and said angular letters and means within each of said compartments for simultaneously illuminating all of said angular letters or said R's.

4. A casing polygonal in cross section, a plurality of windows positioned along at least three of the sides thereof, an angular letter formed on each of said windows, another letter formed on said windows and positioned in the vertexes of said angular letter, upwardly inclined, radially extending partitions issuing from the lines of separation of the legs of said angular letters and said other letters, radially extending vertically positioned walls issuing from the lines of division of said stems of said angular letters and said other letters and from the corners of said casing, intersecting said partitions to form two compartments communicating with all of said other letters and said angular letters and means within each of said compartments for simultaneously illuminating all of said angular letters or said other letters.

5. A casing polygonal in cross section having windows positioned on at least three of the sides thereof, signals formed upon said windows, including a plurality of corresponding elements, one element at least partially embracing the other radially formed partition walls extending from said

windows to the center of the casing to separate the elements of said signals and to form compartments communicating with corresponding elements of all of said signals and means within said compartments for simultaneously illuminating all of the corresponding elements connected with said respective compartments.

6. A casing polygonal in cross section, a plurality of windows positioned along at least three of the sides thereof, a letter L formed on each of said windows, a letter R formed on said windows and positioned in the vertexes of said letters L, upwardly

inclined, radially extending partitions issuing from the lines of separation of the legs of said L's and said R's, radially extending vertically positioned walls issuing from the lines of division of said stems of said L's and said R's and from the corners of said casing, intersecting said partitions to form two compartments communicating with all of said R's and said L's and means within each of said compartments for simultaneously illuminating all of said L's or said R's.

WILLIAM F. BRETTSCHEIDER.
